UNITED STATES PATENT OFFICE.

WERNER I. STAAF, OF PITTSBURGH, PENNSYLVANIA, ASSIGNOR TO EDWARD B. TYLER, OF PITTSBURGH, PENNSYLVANIA.

MECHANISM FOR WEIGHING LIQUIDS.

1,239,839.

Specification of Letters Patent. Patented Sept. 11, 1917.

Application filed June 10, 1916. Serial No. 102,878.

To all whom it may concern:

Be it known that I, WERNER I. STAAF, of Pittsburgh, in the county of Allegheny and State of Pennsylvania, have invented a new and useful Improvement in Mechanisms for Weighing Liquids, of which the following is a full, clear, and exact description, reference being had to the accompanying drawings, forming part of this specification, in 10 which—

Figure 1 is a view partly in side elevation and partly in vertical section of one form of mechanism embodying my invention; and

Figs. 2 and 3 are similar views showing 15 a portion of the mechanism in different positions.

The present invention is more particularly designed as an improvement over the mechanism which is shown and described in the 20 prior patent to Werner I. Staaf, the applicant herein, No. 1,082,614, dated December 30, 1913, and the patent to E. B. Tyler and the present applicant, No. 1,092,082, dated March 31, 1914.

25 One object of the present invention is to provide escapement means of improved character for automatically controlling the discharge of the filled buckets, whereby the operation of the mechanism will be rendered 30 more certain and effective. A further object of the invention is to improve the shape of the buckets employed and to provide a bucket so constructed and arranged that there will be the shortest possible period of time required in diverting the liquid to be weighed 35 from one bucket to another with a minimum tendency to splash.

In the accompanying drawings, the numeral 2 designates the casing of the meter, 40 which is provided with suitable bearings for the meter shaft. The upper portion of the casing has the receiving chamber 3, provided with the approximately central elongated bottom discharge opening 4, substantially as 45 in said Patent No. 1,082,614.

In accordance with my present invention, one end portion of the meter shaft is provided with a cam wheel 5, having thereon a plurality of cam surfaces, one for each 50 bucket 6. Each of these cam surfaces is of gradually increasing radius in the direction of rotation of the bucket, and terminates at its high end in a stop projection 7, whose outer edge projects beyond the peripheral 55 surface of the cam portion. Coöoperating

with this cam wheel is a lever 8, fulcrumed at 9 and having an antifriction roller 10, arranged to travel on the cam wheel. The arm of the lever which carries said roller is provided with an adjustable weight 11. The 60 other arm of the lever has a vertical slot at 12, which engages the pin or stud 13, carried by a cylinder 14, which telescopes over a plunger member 15, pivoted to the casing of the meter at 16.

The plunger member 15 has an air inlet port 17, extending therethrough and controlled by the upwardly opening check valve 17^a. Said plunger member also has an escape port 18, the lower portion of which is designed to be moved into and out of register with an escape or opening 19, in the cylinder member 14.

The slot 12 is preferably made of such length as to have a clearance substantially proportional to the amount of the projection of the outer edge of each of the stops 7 beyond the adjacent peripheral cam portion of the cam wheel 5.

The buckets 6 are of generally triangular 80 form in transverse cross section and are so constructed that the rear wall 6^a of each bucket is in radial relation to the center of the meter shaft, the bottom wall 6^b being at substantially right angles to the wall 6^a 85 throughout the major portion of its length, but preferably curved somewhat, as at 6^c, at its outer end.

By reason of this shape and construction of the buckets, it will be readily seen, by reference to Fig. 1, that the bottom wall 6^b of a following bucket will act to divert the liquid entering through the slot 4 into the preceding bucket 6, in the horizontal filling position, while such bucket is being held in that position by the engagement of the antifriction roller 10 with one of the stops 7. When each bucket becomes filled with a predetermined weight of liquid regulated by the adjustment of the weight 11, the action 90 of the stop 7 against the roller 10 will be overcome, and the shaft and buckets will commence rotating, as indicated in Fig. 2, to move the filled bucket to discharging position. It will be apparent that almost 95 immediately after the bottom of the next following bucket ceases to divert the liquid into the filled bucket, such following bucket, owing to its shape, will be brought 100 into position to receive the discharge; also 110

that by this construction and arrangement, splashing of the liquid will be largely prevented.

After the roller 10 passes over the stop to the position shown in Fig. 3, the shaft will rotate quickly through the next substantially ninety degrees to bring the next bucket into filling position, the roller 10 riding up one of the cam surfaces. When the parts are 10 in the position shown in Fig. 3, the cylinder 14 has been pulled upwardly, so that the ports 18 and 19 are out of register. During the next substantially ninety degrees of movement, the arm of the lever to which the cylinder is attached will be moved downwardly as the roller rides up the cam. As the roller rides up the cam, the arm 8 moves freely until the top of the slot 12 engages the pin 13, after which the cylinder 14 is 20 forced downwardly a short distance quickly compressing the air therein, until the cam wheel is brought to rest by the engagement of the roller 10 by one of the stops 7. The rise of the cam and the length of the slot 12 are preferably so proportioned that the top 25 of the slot 12 engages the pin 13 near the end of the movement of the cam wheel, so that the last part of the movement of the roller over the rise of the cam serves to 30 brake the cam wheel before the wheel is brought to rest by the engagement of the roller 10 by the stop 7. This results in a quick movement of the cam wheel as the roller 10 rides onto the top of the stop 7 35 and continuing until the braking of the cam wheel which occurs when the roller 10 has ridden up the cam 5 far enough to cause pin 13 to be engaged by the top of the slot 12.

It will be noted that it is during the first 40 part of this quicker movement of the cam wheel, that the edge of the uppermost bucket passes across the slot 4, thus providing a quick cutting out and in of the buckets, which takes place immediately after the 45 bucket wheel begins its movement.

Moreover, the slot 4 is so arranged substantially vertically above the bucket shaft and the buckets are so shaped that a bucket which is about to empty as shown in Fig. 2 50 will not begin to empty until the edge of the uppermost bucket has passed across the slot 4, thus insuring that all of the liquid is weighed. When the cylinder is moved from the position shown in Fig. 2 to that shown in 55 Fig. 3, the air is drawn in through the passage 17, past the check valve 17^a, and is trapped by said valve within the cylinder. During the time that the roller 10 remains in contact with the next stop 7, the weight of 60 the cylinder will gradually cause it to move down to the position shown in Fig. 1, this movement being permitted by the clearance in the slot 12, until the ports 18 and 19 are again brought into register. Therefore, at 65 the time the apparatus is again ready to

trip, these parts are in register so as to permit the relatively free escape of air from the cylinder, and thus permit the roller 10 to ride over the stop.

It will be apparent from the foregoing 70 that the cylinder and plunger form an effective controlling device acting in the nature of a dash-pot. It is of great importance in the operation of this device that the apparatus shall not trip until the predetermined 75 weight of liquid has been collected in each bucket, since otherwise, the accuracy of the results obtained would be seriously affected. It is also necessary to guard against any 80 possibility of spinning of the bucket shaft after it has been released and to insure that the next bucket shall be stopped in the correct filling position. These operations are 85 properly insured by the provision of the controlling mechanism described, since it will be apparent that the air trapped in the cylinder 14 will act as an effective brake upon the cam wheel until such time as said cylinder moves to a position to bring the 90 ports 18 and 19 into register.

I do not desire to limit myself to the details of construction and arrangement of the several parts which I have herein shown and described, as it will be obvious that various 95 changes may be made in such details, without departing from the spirit and scope of my invention, as set forth in the appended claims.

I claim:

1. In an apparatus for weighing liquids, 100 the combination with a rotary shaft having a plurality of liquid-receiving buckets or receptacles, of a controlling device for said shaft and buckets, said device comprising a cam member having projecting stops, a 105 weighted lever in engagement with the cam member, and a dash-pot device connected to said lever, substantially as described.

2. In an apparatus for weighing liquids, 110 the combination with a rotary shaft having a bucket, of a cam wheel connected to said shaft and having a cam surface of gradually increasing radius and terminating in a stop whose outer edge projects beyond the cam surface, a weighted lever co-operating with 115 the cam, and a dash-pot device connected to said lever, substantially as described.

3. In an apparatus for weighing liquids, 120 the combination with a rotary shaft having a bucket, of a cam wheel connected to said shaft and having a cam surface of gradually increasing radius and terminating in a stop whose outer edge projects beyond the cam 125 surface, a weighted lever co-operating with the cam, and a dash-pot device connected to said lever, said dash-pot device comprising telescoping cylinder and plunger members having escape ports arranged to be moved into and out of register, substantially as 130 described.

4. In an apparatus for weighing liquids, the combination with a rotary shaft having a plurality of buckets or receptacles, of a cam member connected to said shaft, said member having a plurality of cam surfaces, each of which is of gradually increasing radius in the direction of rotation of said member, a pivoted lever having one arm engaging the cam wheel, and a dash-pot device connected to said lever and having escape openings arranged to be moved into and out of register with each other, substantially as described. 65
5. In mechanism of the character described, the combination of a bucket shaft, a cam member connected to said shaft, a weighted lever adapted to engage the cam member, and a dash pot device having a movable member provided with a lost motion connection with said lever, substantially as described. 70
6. In mechanism of the character described, the combination of a bucket shaft, a cam member connected to said shaft, a weighted lever adapted to engage the cam member, a cylinder having a pin-and-slot connection with said lever, and a plunger over which the cylinder telescopes, said plunger having a valved inlet and the plunger and cylinder having co-operating escape ports, substantially as described. 75
7. In an apparatus for weighing liquids, a bucket shaft and a bucket carried thereby, said bucket being of generally triangular form in transverse cross section having an inner wall in substantially radial relation to said shaft and having a relatively longer bottom wall at substantially right angles to said inner wall, substantially as described. 80
8. In an apparatus for weighing liquids, a bucket shaft and a bucket carried thereby, said bucket being of generally triangular form in transverse cross section having an inner wall in substantially radial relation to said shaft and having a substantially flat bottom wall at substantially right angles to said inner wall, and said bottom wall being curved inwardly at its outer end portion, substantially as described. 85
9. In an apparatus for weighing liquids, a bucket shaft having a plurality of buckets attached thereto and rotating in a step by step movement, and a discharge opening for discharging the liquid to be weighed to the buckets at a point substantially vertically above the shaft, the bottom walls of the buckets being so inclined that the bottom wall of a bucket which is uppermost and substantially vertical will divert the liquid from the discharge opening into the next preceding bucket, substantially as described. 90
10. In an apparatus for weighing liquids, a bucket shaft having a plurality of buckets
- attached thereto, and a discharge opening for discharging the liquid to be weighed to the buckets, the buckets being of a generally triangular form in cross section with inclined bottoms so constructed and arranged with reference to the discharge opening that the bottom of an upright bucket 70 immediately beneath the discharge opening will divert the liquid to the next preceding bucket, substantially as described. 95
11. In an apparatus for weighing liquids, a bucket shaft having a plurality of buckets attached thereto, a discharge opening for discharging the liquid to be weighed to the buckets, means for causing the bucket shaft to rotate in a step by step movement and operating to arrest a bucket with its edge beneath and in close proximity to the discharge opening so as to receive liquid upon a slight initial movement of the bucket shaft in the next subsequent step of its movement, substantially as described. 100
12. In an apparatus for weighing liquids, a bucket shaft having a plurality of buckets attached thereto, a discharge opening for discharging the liquid to be weighed to the buckets, means for causing the bucket shaft to rotate in a step by step movement operating to check the edge of a bucket beneath and in close proximity to the discharge opening and to cause the edge of said bucket to pass quickly across said discharge opening at the beginning of the subsequent step of the movement of the bucket shaft, and thereafter gradually check and finally stop the movement of the bucket, substantially as described. 105
13. In an apparatus for weighing liquids, a bucket shaft having a plurality of buckets attached thereto, a discharge opening for discharging the liquid to be weighed to the buckets at a point substantially vertically above the shaft, means for causing the shaft to rotate in a step by step movement and operating to arrest a bucket with its edge beneath and in close proximity to the discharge opening and to cause the edge of the bucket to quickly pass across the discharge opening on the next subsequent movement of the bucket shaft, the buckets being so shaped that the bottom wall of the bucket whose edge is arrested in proximity to the discharge opening will divert the liquid from the discharge opening forwardly into the next preceding bucket, substantially as described. 110

In testimony whereof, I have hereunto set my hand.
